UNITED STATES PATENT OFFICE

WILLIAM F. FOLMER AND HARRISON L. CHAPIN, OF ROCHESTER, NEW YORK, AS
SIGNORS TO FOLMER-CHAPIN CORPORATION, OF ROCHESTER, NEW YORK, A COR-
PORATION OF NEW YORK

DESIGN FOR AN ELECTRIC LAMP AND HIGH TENSION INSECT DESTROYER

Application filed July 23, 1931. Serial No. 40,662. Term of patent 14 years.

To all whom it may concern:

Be it known that we, WILLIAM F. FOLMER and HARRISON L. CHAPIN, citizens of the United States of America, residing at Rochester, in the county of Monroe and State of New York, have invented a new, original, and ornamental Design for Electric Lamp and High Tension Insect Destroyer, of which the following is a specification, reference being had to the accompanying drawing, forming part thereof.

The drawing is an elevation of an electric lamp and high tension insect destroyer showing our new design. The device is, in general, cylindrical in shape, that is, circular in cross section.

We claim:

The ornamental design for an electric lamp and high tension insect destroyer substantially as shown and described.

WILLIAM F. FOLMER.
HARRISON L. CHAPIN.
